UNITED STATES PATENT OFFICE.

HUGH McCABE, OF LAWRENCE, MASSACHUSETTS.

FLANGING MACHINE.

Application filed February 25, 1921. Serial No. 447,794.

To all whom it may concern:

Be it known that I, HUGH McCABE, a citizen of the United States, residing at Lawrence, in the county of Essex and State 5 of Massachusetts, have invented certain new and useful Improvements in Flanging Machines; and I do hereby declare the following to be a full, clear, and exact description of the invention, such as will enable others 10 skilled in the art to which it appertains to make and use the same.

This invention relates to a flanging machine and more particularly to a flanging machine of the type disclosed in the patent 15 to Hugh McCabe No. 1,030,416, dated June 25, 1912.

Flanging machines of this type operate to form a flange on a metal plate in successive steps. Adjacent increments of the 20 work along an edge thereof are successively bent down until the entire flange has been bent to a position corresponding to the first step in the flanging operation. Thereafter the flange is incrementally bent through the 25 second step and so on until the completed flange has been formed. In the patent above referred to, the flanging machine is provided with a bender 20 mounted upon a segmental bender carrier 190 having a 30 segmental gear 240. A reciprocatory rack 250 capable of being swung into and out of engagement with the segmental gear 240 serves to oscillate the bender 20 through a normal angle of oscillation, approximately 35 40°. During the first step of the flanging operation, the bender is repeatedly oscillated through its normal angle of approximately 40° to form successive incremental bends in the flange portion of 40 the plate, the work being fed along through the machine after each increment of the flange has been bent. Because of the resiliency of the metal, the flange after having been bent down in any step, springs back 45 somewhat. The spring-back of the metal in this manner would operate to interfere with the feeding of the work through the machine during the succeeding step in the flanging operation. Provision is made in 50 the above mentioned patent for repositioning the rack 250 with relation to the segmental gear 240, so that during such successive steps of the flanging operation, the bender is returned, after each increment of 55 the flange has been turned down, to a position clear of the portion of the flange to be

bent down. The rack is repositioned in this manner between successive steps in the flanging operation until the completed flange has been formed. 60

In the above mentioned patent mechanism is disclosed for accomplishing the repositioning of the arc of oscillation of the bender to accomplish this result. This mechanism includes a dog 500 adapted to be 65 automatically moved into the path of the collar 380 whenever the rack is disengaged between successive steps in the flanging operation of the bender. During the return of the bender to its initial position, however, 70 the construction of the mechanism is such as to require a hand operation of the operator to move the dog 500 (by means of a handle 514) to position the dog in the path of the collar 380. The dog 500 is allowed 75 to remain in the path of the collar 380 during the first two successive steps incident to the return of the bender to its initial position, being removed from the path of the collar 380 during the final step, this being 80 done by manually swinging the handle 514 to the right. It will therefore be apparent that the mechanism disclosed in the above mentioned patent, while operating automatically during the advance of the bender 85 requires manual operation during the return of the bender to its initial position.

The object of the present invention is to provide a flanging machine of this type with mechanism for positioning the arc of oscillation of the bender to enable the work to be fed freely through the machine, not only during the advance of the bender but during the successive steps in the return of the bender to its initial position. 90

The invention consists in the flanging machine hereinafter described and particularly defined in the claims.

The drawing illustrates the preferred embodiment of the invention in side elevation. 100

The construction and operation of the flanging machine in general is the same as that disclosed and fully described in the above mentioned McCabe Patent No. 1,030,- 416 to which reference may be had. 105

The mechanism for positioning the arc of oscillation of the bender to enable the work to be fed freely through the machine comprises a positioning device 51, mounted on the rod 390, and held from longitudinal movement on the rod 390, and held from longitudinal movement on the rod by means 110

of two stop collars 52 and 54, a compression and torsion coil spring 55, by expansion tending yieldingly to press the positioning device 51 against the stop collar 52, and by 5 torsion to hold the device in an inoperative or turned down position. One end of the positioning device 51 is provided with an offset nose 61, shown in the drawing in its operative position. This nose is adapted to 10 be struck by the collar 380 projecting from the side of the rack when it is in operative position, and to pass by it when it is in turned down or inoperative position. When the collar 380 strikes the end of the 15 positioning device 51, it shuts off the air valve and stops retracting movement of the rack by the means described in said patent. In the present construction when the collar 380 strikes the nose 61, it stops the retracting 20 movement of the rack at an earlier point.

The clamping wedge 50 is operated by the bell crank lever 80 and piston rod 90 from the cylinder 100, as in said patent. Connections are provided between the wedge 25 operating piston rod 90 and the positioning device for turning the latter up in certain stages in the operation of the machine, and turning it farther up and locking it up in other stages of the operation of the 30 machine, and to this end the piston rod 90 is provided with a bracket 91 which is secured to the piston rod 90, and which supports one end of the positioning device operating rod 92. This rod 92 is further supported by a plate 93 which is fastened on the cylinder 100. The end of the rod 92 is provided with a collar 94, and a spring 95 takes 35 against the collar at one end, and against a chain lever 62 at the other end. The rod 40 92 also carries a pulley bracket 63 carrying a chain pulled. The chain lever 62 pivoted on a stud 67 in the frame of the machine engages the spring 95 at its upper end, and near its upper end is attached a chain 60 45 which runs from the lever over the pulley and down to the positioning device 51. An arm 65 depending from the stud 67 below the lower end of the chain lever 62, is adapted to be engaged by a lug 244 on the segment 50 55 240 when the segment occupies its position of extreme throw, as shown in the drawing. With the segment in this position the chain lever 62 occupies the position shown, and the releasing of the clamping wedge 50 operates 55 to move the pulley bracket 63 to the left, so as thereby to exert a pull upon the chain 60 sufficient to turn the positioning device to its operative position and a little beyond, so as to permit the latch pin 56 to engage 60 the recess 58 in the positioning device 51, thus latching and holding the positioning device in its operative position. When the segment occupies intermediate positions it 65 will be observed that the lug 244 not being in engagement with the depending arm 65, the

chain lever 62 occupies a position inclined to the left, and therefore an added length of chain is provided, so that in the positions of the segment where the rack is disengaged therefrom, or, in other words, in the disengaging positions of the segment, the chain only lifts the positioning device into operative position without turning it far enough to cause the latch pin 56 to engage the recess 58 so as thereby to hold it in its operative position. Therefore, in the use of the machine, after the successive increments of one bend of the flange have been performed and the segment has been brought to its first disengaging position with the recess 310 in position to be engaged by the dog 300, the hand lever 290 will be turned to throw the dog into engagement with the recess, and at the same time to drop the rack out of engagement with the segment. This will turn 70 the positioning device 51 into operative position (but not far enough to latch it in such operative position). Then the rack will be run back until the collar 380 thereon strikes the nose 61 of the positioning device, and through it pushes on the rod 390 so as to thereby stop the retracting movement of the rack, as described in said patent. During 75 this operation the chain may be said to be in its lengthened position because the chain lever 62 is tipped to the left. The lever 290 will now be swung to the left in the position shown in full lines, thereby re-engaging the rack, and the second step of bending is carried on as before by successive increments 80 until the second step of bending is completed, whereupon the recess 370 of the bender segment will be engaged by the dog 300, the rack will be dropped to disengagement 85 from the segment, the positioning device will be lifted to operative position, and the rack will be run back as before. The third step 90 of the bending operation will now be performed, progressing by successive increments 95 bendings in which the segment advances to the position shown in full lines, the lug 244 will have struck the tail of the chain lever 62 and exerted a pull upon the 100 chain which will lift the positioning device 105 51 to a certain extent, but upon each retracting stroke of the bender segment the positioning device 51 will turn back to inoperative position because the clamping wedge 50 will not be released until the last 110 increment of the bend being given the flange is completed, and then, before retracting the bender, the clamping wedge 50 will be released and this will turn the positioning device up to its operative position and lock 115 it in such position. The rack will now be run back while it is still engaged with the segment until the collar 380 strikes the nose 61 of the positioning device 51, whereupon the rack will be disengaged, run forward, 120 and re-engaged, the positioning device 125 130

standing fast the while. The rack will now be re-engaged and run back, bringing the recess 310 opposite the dog 300 (the positioning device standing fast in operative position) until the collar 380 strikes the nose 61 of the positioning device. The rack will then be disengaged, run forward, and re-engaged and retracted, and during its retracting movement, or at the end of its retracting movement, the operative will disengage the positioning device from the latch pin 56 by pushing on the handle 59 to compress the spring 55, and then the rack may be run back the remainder of the distance to its initial position. Upon the release of the positioning device by the use of the handle, which may be operated by the hand or by the foot, the torsion of the spring will turn the positioning device to inoperative position. It will thus be seen that the machine operates automatically to regulate the position of the bender face, so as to permit the feeding of the work to the machine during the successive steps of bending the flange down, whereupon the releasing of the clamping wedge at the end of the flange bending operation raises the positioning device into locked operative position where it remains during the resetting actuation of the machine to bring the bender segment back to within a small angle of its initial position, whereas, in the machine of said patent the positioning device was required to be operated by a separate operation of the hand at the end of the flanging operation to throw the pawl 500 into operative position. In the present machine the corresponding member, namely the positioning device, is thrown into operative position at the end of the flange bending operation by the operation of releasing the clamping wedge. It will be observed that there are two men required to operate the machine, the one being a helper to present the work to the machine, and the other the operator proper, who works the

controls for the machine. The latter stands with the right hand on the valve 280 for controlling the oscillations of the bender and with the left hand on the valve 110 for controlling the clamping wedge 50. The present construction enables the operator to throw the positioning device into locked operative position by the wedge valve instead of reaching down and turning it up by an inconvenient hand operation.

Having thus described the invention, what is claimed is:—

1. A flanging machine of the step flanging type having, in combination, an oscillating bender, bender actuating means, a work clamp, clamp actuating means, a clamp controller for controlling the movements of clamp actuating means to clamp the work, a positioning device for positioning the arc of oscillation of the bender, and means connected with the clamp actuating means for operating the positioning device.

2. A flanging machine of the step flanging type having, in combination, an oscillating bender, bender actuating means, a work clamp, clamp actuating means, a positioning device for positioning the arc of oscillation of the bender, and means connected with the clamp actuating means for operating the positioning device.

3. A flanging machine of the step flanging type having, in combination, a bender, bender actuating means, a work clamp, clamp actuating means, a positioning device for the bender, and means connected with the work clamp and bender actuating means for operating the positioning device.

4. A flanging machine having, in combination, a bender, bender actuating means, a work clamp, clamp actuating means, a positioning device for the bender, and means controlled by the position of the bender for operating the positioning device.

HUGH McCABE.
